No. 7. 141.

Jan. 27. 1874.

W. H. Chapman *W. H. Chapman*

UNITED STATES PATENT OFFICE.

GEORGE F. MEACHAM, OF NEWTON, ASSIGNOR TO JAMES W. TUFTS, OF MEDFORD, MASSACHUSETTS.

DESIGN FOR THE CASING OF A SODA-WATER APPARATUS.

Specification forming part of Design No. 7,141, dated January 27, 1874; application filed December 15, 1873.
[Term of Patent 14 years.]

C.

To all whom it may concern:

Be it known that I, GEORGE F. MEACHAM, of Newton, in the county of Middlesex and State of Massachusetts, have invented and produced a new and original Design for the Casing of a Soda-Water Apparatus, of which the following is a full, clear, and exact description, reference being had to the accompanying photograph making part of this specification.

In the photograph, A represents the lower or main portion of the casing of a soda-water apparatus, which is of hexagonal form, each side having an ornamental top, b. Above the portion A, and within the ornamental tops b, is a smaller hexagonal portion, B, so placed that each of its angles will be half-way between two adjacent angles of the lower portion A. The portion B is provided with an

ornamental top, C, and is surmounted by a hexagonal pyramidal cap, D, the design thus produced being unique and ornamental.

What I claim as my invention, and desire to secure by Letters Patent, is—

The design for the casing of a soda-water apparatus, consisting of hexagonal portion A, provided with the ornamental top b, and surmounted by the smaller hexagonal portion B, and crowned by the hexagonal pyramidal cap D, as herein shown.

Witness my hand this 10th day of December, A. D. 1873.

GEO. F. MEACHAM.

In presence of—

P. E. TESCHEMACHER,
G. A. MEACHAM.
